[57] CLAIM

We claim the ornamental design for a dump truck body, as shown and described.

DESCRIPTION

FIG. 1 is a perspective view of the dump truck body showing our new design;

FIG. 2 is a left side view of the dump truck body, the right side elevational view being a mirror image;

FIG. 3 is a front elevational view of the dump truck body;

FIG. 4 is a rear elevational view of the dump truck body; and,

FIG. 5 is a top plan view of the dump truck body. The broken lines shown are for illustrative purposes only and form no part of the claimed design.
